Patented May 28, 1918.

UNITED STATES PATENT OFFICE.

ISIDOR GISSER, OF BROOKLYN, NEW YORK.

LOCK.

1,267,860.

Specification of Letters Patent. Patented May 28, 1918.

Application filed October 8, 1917. Serial No. 194,435.

To all whom it may concern:

Be it known that I, ISIDOR GISSER, a subject of the Government of Russia, residing at the borough of Brooklyn, county of 5 Kings, city and State of New York, have invented certain new and useful Improvements in Locks, of which the following is a specification.

The invention relates to improvements in 10 locks and has particular reference to the type of locks usually placed upon doors.

The primary object of the invention is the provision of a lock which is simple in construction, easily operated with the proper 15 key and which can be produced at small cost.

Another object of this invention is to provide a lock in which a large variety of keys 20 may be used, one key varying very slightly from the other, but only one type of key operating a given lock.

I obtain this object by using a lock provided with the usual form of sliding bolt upon one side of which I provide several 25 notches thereby forming teeth similar to that in a rack. Immediately, above the teeth of the bolt and in the side of the lock, I provide a circular aperture or keyway to receive the key, which is preferably circular 30 in cross section. At the end of the key, I provide a short lever, which is hingedly attached to the former. When the key is inserted into the aperture, the hinged lever is adapted to drop down until it is at right 35 angles to the key and thereby engages with the teeth in the sliding bolt. If the key now be turned, the bolt will move in or out of position.

Other details and advantages of my device will be apparent from the detailed description and the accompanying drawing 40 forming a part of this specification in which similar numerals refer to similar parts in all the views, and in which Figure 1 is a plain view of a lock with the top plate removed, showing the interior; Fig. 2 is a section taken on line 2—2 of Fig. 1 and showing 45 a key in position; Fig. 3 is a section on line 3—3 of Figs. 1 and 2; Fig. 4 is a side view of a key; Fig. 5 is a side view of a key at right angles to that of Fig. 4; Fig. 6 is a section taken on line 6—6 of Fig. 2 showing 50 a cross section of a key and the keyway, and Fig. 7 is a section showing a modified key way.

Referring to the drawings, the lock con-

sists of the outer casing 1 and the cover 2 which is provided with a projecting cylindrical keyway 4 which is adapted to fit into a hole in the door to which the lock is attached. The bolt 5, preferably rectangular in cross section is provided with a number of teeth 6 and is adapted to slide within the casing 1 passing through the slot 7 in the side of the latter. The bolt 5 is held 60 in position by means of the outer and bottom plates of the casing 1, the slot 7, the lugs 8 and 9, and the plate 3 attached to the cover 2. The key 10 is circular in cross section and is provided at its end with a lever 11 which is hingedly connected to it by means of pin 12. The lever 11 when folded over will fit into the slot 13. The key 10 is inserted into the hole in the keyway 4 until its end fits into the hole 14 in 65 the outer plate of the casing 1. This permits the lever 11 to assume a position at right angles to the key 10 in which case its end engages with the teeth 6 of the bolt 5. It will now be evident that when the key 70 10 is turned in the keyway 4, the bolt 5 will be moved so as to either engage or disengage with the catch 15. The key 10 is provided with one or more projecting pins 18 and 19 which pass through the corresponding grooves 16 and 17 in the keyway 4. The pin 18 is located so as to clear the keyway 4 when the key is inserted into its full depth, while the pin 19 is located so as to slide within the annular groove 20 when 75 the key is rotated.

In order to have a large variety of keys, the position of the groove 20 and its corresponding pin 19 is varied in the different locks. Similarly the angular relation between the grooves 16 and 17 is varied as is clearly brought out in Figs. 6 and 7. If desired an additional longitudinal groove parallel to the grooves 16 and 17 and its corresponding pin on the key may be used or a transverse groove parallel to groove 20 and a corresponding pin on the key may be added. The locks and keys may also be varied by varying the length of the lever 11 and the corresponding distance between the center of the key and the top of the teeth 6 on the bolt 5.

In order to lock the bolt 5 in position, I provide the following: The bar 22 having its end 23 shaped so as to fit between the teeth 6 of the bolt 5, has a horizontal portion 25 which is provided with a hole fitting over the

pin 24 and a tapered portion 26. When the key is not within the lock, the bar 22 will drop down due to the action of gravity until its end 23 engages with one of the teeth 6 5 and thereby will lock the bolt 5 in position. If desired a spring may be used to assist gravity in keeping the end 23 of the bar 22 engaged with the teeth 6. When the key is inserted into the keyway 4, its end will press 10 against the tapered portion 26 of the bar 25 until it is raised and thereby the end 23 of the bar 22 is disengaged from the teeth 6.

If it be desired to lock the bolt 5 on the inside of the room so that the lock could not 15 be opened with the key from the outside, the knob 28 may be moved within the slot 29 until its end comes over the projecting lug 27 of the bar 22 and thereby locks the end 23 against the tooth 6, so that it cannot be 20 raised with the key.

The bolt 5 may be moved laterally without the aid of a key on the inside of the room by means of the knob 30 fixed to the bolt 5 and sliding within the slot 31 in the casing 1.

Copies of this patent may be obtained for five cents each, by addressing the "Commissioner of Patents, Washington, D.C."

It is evident that modifications of the construction shown herewith may be made employing the general features herein disclosed, I therefore do not wish to limit myself to the exact construction shown, but wish to claim all equivalents. 25

Having thus described my invention, I 30 claim as new and wish to secure by Letters Patent.

In a lock, the combination of a bolt having notches at the side thereof, a key having a lever hingedly attached to the end thereof adapted to engage with said notches and thereby move said bolt when the key is turned, a bar hingedly attached to the casing of the lock adapted to have its end engage 40 with one of the notches in the bolt and thereby lock it in position, and means for raising said bar by the insertion of the key.

Signed at New York, in the county of New York and State of New York, this 25th day 45 of September, 1917.

ISIDOR GISSER.
